UNITED STATES PATENT OFFICE.

ROBERT S. MOORE, OF WASHINGTON, DISTRICT OF COLUMBIA, ASSIGNEE TO GYRO MOTOR COMPANY, OF WASHINGTON, DISTRICT OF COLUMBIA, A CORPORATION OF DELAWARE.

INTERNAL-COMBUSTION ENGINE.

1,209,743.

Specification of Letters Patent. Patented Dec. 26, 1916.

Application filed January 29, 1913. Serial No. 744,973.

To all whom it may concern:

Be it known that I, ROBERT S. MOORE, a citizen of the United States, residing at Washington, in the District of Columbia, have invented certain new and useful Improvements in Internal-Combustion Engines, of which the following is a description, reference being had to the accompanying drawing and to the figures of reference 10 marked thereon.

My invention relates to new and useful improvements in rotary gas engines, and more especially to gas engines of the type wherein a plurality of cylinders are carried 15 by a rotating casing, and wherein a piston in each cylinder co-operates with a stationary crank to rotate the casing and cylinders.

The object of the present invention is so 20 to construct the cylinders that in the rotation thereof air will be circulated more effectively against the walls thereof, and undue heating avoided. I accomplish this object by providing the cylinder with tubular 25 radiations forming a part of the body of the cylinder, the tubes being formed by boring longitudinally along the wall of the cylinder, the tubes opening at either end to the atmosphere.

The invention consists in the matters here- 30 inafter described and referred to in the appended claims.

The invention is illustrated in the ap- pended drawings, in which,—

Figure 1 is a plan view of a revolving cyl- 35 nder motor, partly in section, with the cyl- inders constructed in accordance with my in- vention; Fig. 2 is a cross section of one of the cylinders; and Fig. 3 is an elevation partly in section.

In these drawings, the rotary gas engine 40 is of the well known "gyromotor" type, and comprises the casing 1, carrying the plurality of cylinders 2, in each of which is the piston 3 driven by the connecting rod 4 from the stationary crank shaft. The intake valve 45 is represented conventionally at 6, and the discharge valve for the burnt gases at 7. It is not necessary to describe any of these parts in detail, as in general they are of a well known construction.

The feature of this invention is in the means for cooling the motor, and this is ac- 50 complished by the special construction of the cylinders 2. Each cylinder 2 is formed with

an enlarged head or outer portion 8, and 55 through this enlarged portion are bored longitudinal openings 9, at suitable distances apart, and the wall of the cylinder between the openings is milled out, as shown at 10, thus making a scalloped effect to the outer 60 periphery of the cylinder head, and forming in effect tubular radiations open at the bottom and top, through which air may freely circulate and cool the cylinders.

I do not claim to be the first to provide a 65 jacket for a cylinder, arranged thereon to form a space for the circulation of air, or a cooling medium, but by forming the cylinder with tubular radiations and with such tubes integral with the body thereof, I have 70 thereby provided a most effective cooling arrangement for the cylinders, and one especially adapted for revolving cylinder motors.

The outer end or top of the cylinder is 75 preferably provided with radial fins 11 of the usual construction, and at the lower or inner ends of the tubes the boring out thereof leaves longitudinal radiating ribs 12 and 80 grooves 13 between them.

It will be seen that the radial tubes for 85 cooling the cylinders extend to the top of the latter, and by this arrangement it will be seen that when the motor is revolving, the rapid passing of the tubes through the air will suck the air through the tubes in an outward direction in a similar manner, as occurs when air is blown across the end of a tube. This action is aided by the fact which I have observed that in a revolving cylinder 90 motor a strong air current passes from the central section of the motor to its periphery all around the motor.

Having thus described my invention, what I claim as new and desire to secure by Letters Patent, is:—

1. An internal combustion engine includ- 10 ing a rotating casing, cylinders carried thereby and projecting radially therefrom, each cylinder having an enlarged portion adjacent its outer end, said enlarged portion being bored out longitudinally of the cylinder to provide a series of tubes open at the top and bottom to the atmosphere.

2. An internal combustion engine includ- 15 ing a rotating casing, cylinders carried thereby and projecting radially therefrom, each cylinder having an enlarged portion ad-

2
jacent its outer end, said enlarged portion being bored out longitudinally of the cylinder to provide a series of tubes open at the top and bottom to the atmosphere, said enlarged portion of each cylinder being provided with grooves between the tubes to form a scalloped periphery.

In testimony whereof, I affix my signature in the presence of two witnesses.

ROBERT S. MOORE.
